ELECTRICAL SWITCH

Robert A. Gesellschap, Kirkwood, Mo., assignor
to James R. Kearney Corporation, St. Louis,
Mo., a corporation of Missouri

Application July 9, 1948, Serial No. 37,810

3 Claims. (Cl. 200—48)

1

This invention relates generally to electrical switches, and more specifically to an electrical switch which is adapted particularly for use as a part of a gang switch structure, the predominant object of the invention being to provide a switch of this type which, because of its improved construction and arrangement, is capable of performing its intended function in an improved and highly efficient manner.

Fig. 1 is a side elevation of the improved switch of this invention with parts of certain insulators of the switch broken away.

Fig. 2 is an enlarged elevational view of a portion of the improved switch.

Fig. 3 is a horizontal section taken on line 3—3 of Fig. 2.

Fig. 4 is a horizontal section on a reduced scale which is taken on line 4—4 of Fig. 2.

Fig. 5 is a fragmentary elevational view of a portion of the improved switch.

Fig. 6 is a plan view of the portion of the switch which is illustrated by Fig. 5.

Fig. 7 is a fragmentary elevational view of the forward portion of the improved switch.

Fig. 8 is a plan view of the forward portion 25 of the switch which is illustrated by Fig. 7.

Fig. 9 is an enlarged vertical section taken on line 9—9 of Fig. 1.

Fig. 10 is an enlarged vertical section taken on line 10—10 of Fig. 1.

Fig. 11 is an enlarged vertical section taken on line 11—11 of Fig. 1.

In the drawings, wherein is shown for the purpose of illustration, merely, one embodiment of the invention, A designates the improved switch generally in Fig. 1. The switch A includes a base member 1 which may be channel shaped in cross section, and this base member is mounted on suitable spaced supports 2, which in Fig. 1 are illustrated as I beams. At the left-hand or rear end of the switch A, as said switch is illustrated in Fig. 1, an insulator 3 is supported by said base member 1 and extends upwardly therefrom, a suitable mounting 4 being provided for said insulator 3 which is secured at its bottom to the base member and has the insulator 3 secured thereto at the top of said mounting. The insulator 3 has secured thereto at its top face, by fastening devices 5, a terminal 6, an incoming electrical conductor 7 being electrically connected to said terminal 6 by a clamping head 8 which is drawn toward the terminal by bolts 9 so as to clamp an end portion of the incoming conductor between the terminal and the clamping head (Fig. 9).

At the right-hand or forward end of the switch, as said switch is illustrated in Fig. 1, an insulator 10 is supported by the base member 1 and extends upwardly therefrom, there being a suitable mounting 11 for said insulator 10 which is secured to the base member at its bottom and has the insulator 10 fixed thereto at its top. The insulator 10 has fixed thereto at its top face a terminal 12, fastening devices 13 being employed for securing said terminal to said insulator. The terminal 12 is provided with an upwardly extended portion 14, and its opposite end portion projects forwardly of the insulator 10, as shown in Fig. 1, and has an outgoing electrical conductor 15 secured thereto by means of a clamping head 16 resembling the clamping head 8 previously described herein. The upstanding portion 14 of the terminal 12 has formed therein an opening 17 which is open at the top edge of said upstanding terminal portion and extends downwardly thereof, said opening being flared with its greatest width at the top edge of the upstanding terminal portion 14.

Mounted at the forward end of the switch A is an element 18 which is formed of inherently resilient material. The element 18 includes a horizontally extended portion 18' at its lower end whose lower face contacts with a top face portion of the terminal 12, said element portion 18' being secured to said terminal 12 and to the insulator 10 by one of the fastening elements 13 which serve to secure said terminal 12 to said insulator 10, as previously stated herein. From the forward end of the horizontal portion 18' of the element 18 a lower portion 18a extends upwardly and inclines forwardly to a slight degree to the approximate longitudinal center of the upstanding portion of the element, and from this point an upper element portion 18b extends upwardly and inclines rearwardly to a slight degree. At its top, the element 18 is provided with an upwardly and forwardly inclined portion 18c.

At its forward portion the terminal 6 has fixed to its upper face a pair of bars 19 which are spaced apart transversely of said terminal, said bars being secured to said terminal by fastening devices 20, and portions 6' of the terminal 6 being bent upwardly into engagement with the forward faces of said bars (Fig. 5). The terminal 6 has an opening 21 formed therethrough through which an extension 22 is projected, this extension 22 being a part of a head 23 which is secured by fastening devices 24 to the upper end of an insulator 25. The insulator 25 is supported for axial

rotation by a bearing 26 which is disposed vertically in an opening 25' formed in the base 1 (Fig. 2), said bearing including a flange portion 27 which is secured by fastening devices 28 to the base 1.

Secured to the insulator 25 at the lower face thereof is an operating arm 29, a portion 29' of this operating arm being interposed between the lower face of the insulator 25 and the flanged upper portion 30' of a member 30, as is shown to good advantage in Fig. 2, and said member and said operating arm being secured to the insulator 25 by suitable fastening elements 31. The member 30 includes upper and lower cylindrical portions 32 and 33 which are joined by an arcuate web 34, said web preferably being formed integral with said cylindrical portions 32 and 33. The member 30 is supported by the bearing 26 through the instrumentality of a vertically disposed shaft 25, said shaft being extended through the bearing 26, through the lower portion of the upper cylindrical portion 32 of the member 30, and through the lower cylindrical portion 33 of said member 30, and said shaft being provided at its opposite ends with cotter pins 35. Interposed between the upper and lower faces of the bearing 26 and adjacent faces of the member 30 are sets of washers 37 which serve as spacers, and secured to the flange portion 27 of the bearing 26 by a pair of the fastening elements 28 is a bar 38 whose forward end face serves as an abutment element for the member 30.

From the foregoing it is obvious that when the outer end of the operating arm 29 is subjected to rotary movement, the insulator 25 and the member 30 will be subject to like rotary movement, said member rotating about the axis of the shaft 25. Also, when the member 30 starts its rotary movement an end portion of the arcuate web 34 of said member contacts with the forward end face of the bar 38 so that the proper starting position of the member 30 is established.

The improved switch A includes a switch blade 39 comprised of a pair of spaced, elongated elements 39a and 39b. The elements 39a and 39b are pivotally attached at their near ends to the spaced bars 19 by a pivot rod 40, said pivot rod being retained in place by cotter pins 41. At the forward end of the switch blade 39 the elongated elements 39a and 39b support a lever structure 42, said lever structure comprising a pair of spaced members 43, which are provided at their forward ends with an outwardly extended hub portion 44. The lever structure 42 is pivotally attached to the elements 39a and 39b by a pivot rod 45 which extends through openings formed through the elements 39a and 39b and the openings through the hub portions 44 of the spaced members 43. The members 43 are provided with outwardly extended flanges 46 at the lower faces of which a transverse bar 47 is secured by fastening elements 48, the opposite, outer end portions of said bar 47 extending beneath and contacting with the elements 39a and 39b of the switch blade 39.

The extension 22 of the head 23 which is secured to the insulator 25 has formed thereon, or fixed thereto, an eccentric 49 (Figs. 5 and 6) which rotates with said head and insulator when same are subjected to rotary movement in the operation of the switch A. The eccentric 49 is disposed within an eccentric housing 50 which is open at its bottom and at its sides; in other words, the eccentric housing comprises an inverted U-shaped structure having a top wall and

forward and rear walls. Also, the eccentric housing is provided with a pair of spaced upstanding flanges 51 which extend longitudinally of said housing and terminate at the forward end of the housing in spaced ears 51a and at the rear end of the housing in spaced ears 51b. Additionally, eccentric housing is provided with wear plates 52 which are secured to the inner faces of the forward and rear walls of said eccentric housing and with which the peripheral face of the eccentric 49 contacts. The spaced ears 51b have pivotally connected therebetween, by means of a pivot pin 53, the upper end of a link 54, the opposite end of said link being pivotally connected by a pivot element 54' to and between the bars 19 which are fixed to the terminal 6 (Figs. 5 and 6).

Pivots supported by the pivot rod 40 is a lever 55 which is bifurcated at its forward end, as is shown in Fig. 6, said lever 55 being shaped as is shown to good advantage in Fig. 5. The lever 55 is provided with a portion 56 which is interposed between the ears 51a of the eccentric housing 50, there being provided a pivot pin 57 which pivotally attaches said lever portion 56 to said spaced ears 51a of the eccentric housing 50. Pivots attached to the outer end of the lever 55 by means of a pivot pin 58 is a coupling member 58, said coupling member having a screwthreaded socket which receives the rear screwthreaded end portion of a rod 59. The rod 59 extends forwardly of the switch and inclines downwardly slightly, and said rod at its forward end has fixed thereto a latching member 60, the upper portions 43' of the spaced members 43 of the lever structure 42 being disposed outwardly of the opposite sides of said latching member 60 and being pivotally attached thereto by a pivot pin 61. The element 18 has secured thereto an abutment element 62 which is provided with a shoulder 62a at its lower end and an inclined face 62b at its upper end (Fig. 7), the forward portion of the latching member 60 being adapted to engage the shoulder 62a of the abutment element 62 to retain the forward portion of the blade of the switch A in its normal, lowered position.

The rod 59 is supported for sliding movement by a bracket 63, which is shaped as is shown to good advantage in Fig. 10, said bracket being secured by set screws 64 to the spaced, elongated elements 39a and 39b and having an opening 65 through which the rod 59 slidably extends. Also, the spaced, elongated elements 39a and 39b are connected together by a pair of tie elements 66 which are shaped as is shown in Fig. 11 and are provided with arcuate end portions 66' that partially embrace said spaced, elongated elements. The flanges 46 of the spaced members 43 of the lever structure 42 have secured thereto the opposite ends of a spring element 67, there being eyes 68 formed at the opposite ends of said spring element through which shank portions of the fastening elements 48 extend. The spring element includes opposed portions 69 which extend upwardly from the eyes 68 and merge into coiled portions 70, and an elongated, rearwardly extended loop portion 71 which emerges from said coiled portions 70 and is inclined upwardly to a slight degree, as is shown to good advantage in Fig. 7, the bridge portion 72 of said loop portion being in contact with the upper portion of the rod 59. The spring element 67 is under such tension that it tends to maintain the rear part of the lever structure 42 in its normal elevated

position, as said lever structure is illustrated in Fig. 7.

When, in the use of the improved switch disclosed herein, the switch is in the closed-switch position as is shown in Fig. 1, and it is desired to move the switch blade of said switch to the open-switch position, the operating arm 29 is moved in an arc of a circle. Such movement of the operating arm subjects the insulator 25 and the head 23 to rotary movement with the result that the eccentric 49 will move the eccentric housing 50 rearwardly. The initial portion of the rearward movement of the eccentric housing draws the rod 59 rearwardly a sufficient distance to free the forward portion of the latching member 60 from the shoulder 62a of the abutment element 62, and continued rearward movement of the eccentric housing 50 will, because of its attachment to the lever 55, swing the switch blade 39 comprised of the spaced, elongated elements 39a and 39b, upwardly and rearwardly to the position shown by dotted lines in Fig. 5. When the rod 59 is initially moved rearwardly, as described above, the rear part of the lever structure 42 is moved downwardly in opposition to the force exerted by the spring element 67, the spaced members 43 of lever structure 42 contacting with the wall at the base of the opening 17 of the upstanding portion 14 of the terminal 12. This creates a wedging action which effectively separates the elongated elements 39a and 39b from the upstanding portion 14 of the terminal 12 even under icing conditions. When the force which tends to move the rod 59 rearwardly is discontinued the spring element 67 will restore the rod 59 to its normal position relative to the spaced, elongated elements 39a and 39b.

When the switch blade 39 is in the open-switch position, as is illustrated by dotted lines in Fig. 5, and it is desired to move it to the closed-switch position, the operation described above is reversed; that is to say, the operating arm 29 is moved in a direction to cause the eccentric 49 to move the eccentric housing 50 forwardly, whereby the switch blade 39 is moved forwardly and downwardly, the forward portion of the latching member 60 engaging the inclined face 62b of the abutment 62 and engage the lower shoulder 62a thereof. Because of the latching engagement between the latching member 60 of the rod 59 and the abutment element 62 the forward portion of the switch blade 39 of the switch is prevented from bouncing or rebounding in the event said switch blade is closed in a forcible manner.

The lever structure 42 is provided with a downwardly projected extension 73 which moves forwardly into contact with the rear face of the element 18 when said lever structure is moved about the pivot rod 45 upon opening operation of the switch. Thus, any arc which is produced as a result of the opening of the switch will be drawn between the extension 73 and the upper portion of the element 18 as said extension 73 moves away from said upper portion of said element, the upper portion of the element 18 serving as an arcing horn. It is to be noted that the elongated elements 39a and 39b of the switch blade 39 contact closely with opposed outer edges of the upstanding portion 14 of the terminal 12, as is shown at 74 in Fig. 8, whereby good electrical contact between said parts is obtained when the switch is in the closed-switch position. Also, the elongated elements 39a and 39b of the switch blade 39 are provided

with contacts 75 (Fig. 6) which closely engage outer edges of the upturned portions 6' of the terminal 6 so as to provide good electrical contact at these points when the switch is in the closed-switch position. In this connection it is pointed out that the tie elements 66, because of their shape as illustrated in Fig. 11, tend to draw the elongated elements 39a and 39b toward each other so as to cause said elongated elements to make good contact with the outer edges of the upstanding portion 14 of the terminal 12 and with the upturned portions 6' of the terminal 6.

I claim:

1. An electrical switch comprising a switch blade, means for pivotally supporting said switch blade for movement, an incoming terminal for conducting electrical energy to said switch blade, an outgoing terminal into and out of contact with which said switch blade is movable, means for subjecting said switch blade to movement, an element associated with said outgoing terminal which serves as an arcing horn, and means for latching said switch blade to said element when the switch blade is in the closed-switch position, the last-mentioned means comprising an abutment mounted on said element, a latching member movable with said switch blade and with respect thereto and adapted for engagement with and disengagement from said element, a rod connected to said latching member and movable with and with respect to said switch blade by said means for moving said switch blade, said rod serving to move said latching member to its unlatched position with respect to said abutment of said element, a lever structure pivoted to said switch blade and pivoted to said latching member and adapted to contact with said outgoing terminal for breaking contact between said switch blade and said outgoing terminal on opening movement of said switch blade, and spring means connected to said lever structure and engaging said rod for urging said lever structure toward its normal position relative to said switch blade.
2. An electrical switch comprising a switch blade, means for pivotally supporting said switch blade for movement, an incoming terminal for conducting electrical energy to said switch blade, an outgoing terminal into and out of contact with which said switch blade is movable, means for subjecting said switch blade to movement, an element associated with said outgoing terminal which serves as an arcing horn, and means for latching said switch blade to said element when the switch blade is in the closed-switch position, the last-mentioned means comprising an abutment mounted on said element, a latching member movable with said switch blade and with respect thereto and adapted for engagement with and disengagement from said element, a rod connected to said latching member and movable with and with respect to said switch blade by said means for moving said switch blade, said rod serving to move said latching member to its unlatched position with respect to said abutment of said element, a lever structure pivoted to said switch blade and pivoted to said latching member and adapted to contact with said outgoing terminal for breaking contact between said switch blade and said outgoing terminal on opening movement of said switch blade, and spring means connected to said lever structure and engaging said rod for urging said lever structure toward its normal position relative to said switch blade.
3. An electrical switch comprising a switch blade, means for pivotally supporting said switch blade for movement, an incoming terminal for conducting electrical energy to said switch blade, an outgoing terminal into and out of contact with which said switch blade is movable, means for subjecting said switch blade to movement, an element associated with said outgoing terminal which serves as an arcing horn, and means for latching said switch blade to said element when the switch blade is in the closed-switch position, the last-mentioned means comprising an abutment mounted on said element, a latching member movable with said switch blade and with respect thereto and adapted for engagement with and disengagement from said element, a rod connected to said latching member and movable with and with respect to said switch blade by said means for moving said switch blade, said rod serving to move said latching member to its unlatched position with respect to said abutment of said element, a lever structure pivoted to said switch blade and pivoted to said latching member and adapted to contact with said outgoing terminal for breaking contact between said switch blade and said outgoing terminal on opening movement of said switch blade, and spring means connected to said lever structure and engaging said rod for urging said lever structure toward its normal position relative to said switch blade, and an extension

on said lever structure which is adapted to contact with said element during switch-opening movement of said switch blade.

3. An electrical switch comprising a switch blade, means for pivotally supporting said switch blade for movement, an incoming terminal for conducting electrical energy to said switch blade, an outgoing terminal into and out of contact with which said switch blade is movable, and means for subjecting said switch blade to movement, the last-mentioned means comprising a rotatable member provided with an eccentric, an eccentric housing which receives said eccentric therein and is subjected to movement thereby, a pivotally supported lever to which said eccentric housing is pivotally connected, an elongated element which is pivotally connected to said lever, a lower structure for connecting said elongated element to said switch blade for movement with said switch blade and with respect thereto, said lever structure serv-

ing on switch-opening operation of the switch to break contact between said switch blade and said outgoing terminal by moving against a portion of said outgoing terminal, and spring means connected to said lever structure and engaging said elongated element for urging said lever structure toward its normal position relative to said switch blade.
